Clifford Nutt.

Case "6"

Letters Patent.

The Schedule referred to in these Letters Patent and making part of the same, containing a description in the words of the inventor, Clifford Nutt himself of his improvement in the construction of the tops of stoves by a combination of sections cast separately.

Case "No. 6."

Specification of an improvement made in the construction of the tops of coal stoves by a combination of sections, either cast separately or formed by dividing the same after having been cast entire. Whereas inconvenience has arisen from the casting of the tops of coal stoves, which tops have hitherto been cast entire, therefore an improvement has been introduced and the same having been tested by repeated experiments is deemed worthy of being carried into general use. which improvement consists in casting each top for stove of common size into two separate sections and for very large stoves into four separate sections or if said tops are cast entire in dividing the same according to their size into two or four sections and in either case, whether cast in sections, in combining said sections in one whole; which may be effected by placing the corresponding sections together either overlapping or interlocking the same, or both, at the lines of junction with a flat sufficienly extended to admit equally on each side of said line, of the passage of a bolt thus: and when thus the corresponding end of each section overlaid or underlaid thereby; if the flat overlay the sections to be integrated thereby, which is preferred, as it will then cover the seam that would otherwise be exposed, it may be so formed as to resemble a vine springing up from below and over spreading the integrated sections.

J. H.

For further information reference may be had to the drawing and explanations hereto appended.

Summary.

The improvement above contemplated, consists in preventing the tops of bathtubs and stoves from cracking by casting the same in separate sections, or by dividing the same into sections cast entire and thereafter combining said sections together in manner aforesaid. I therefore claim as my invention the improvement the preventing of the tops of stoves from cracking, by casting the same in sections, or by dividing the same into sections when cast entire, & thereafter combining said sections in one whole as aforesaid together with the uses to which the same has been or may hereafter be applied in stoves or furnaces,--
